UNITED STATES PATENT OFFICE.

DON W. SCHAEFFER, OF DAYTON, OHIO, ASSIGNOR OF ONE-HALF TO GEORGE T. NEUFFER, OF DAYTON, OHIO.

ADJUSTABLE SHORE.

Application filed February 12, 1923. Serial No. 618,495.

To all whom it may concern:

Be it known that I, DON W. SCHAEFFER, a citizen of the United States, residing at Dayton, in the county of Montgomery and State of Ohio, have invented certain new and useful Improvements in Adjustable Shores, of which the following is a specification, reference being had therein to the accompanying drawing.

10 My invention relates to adjustable shores and similar structures.

It is the object of my invention to provide a cheap, strong and easily adjusted shore which can be operated in restricted locations 15 by labor of little skill.

It is a further object of my invention to provide a shore that has a minimum of adjustments, that will not permit the supported member to twist on the supporting member, and which will positively grip the supported member.

It is a further object of my invention to provide an adjustable shore having a coarse adjustment and a fine adjustment.

25 It is an additional object to provide a self-aligning adjustable shore which will insure the application of the weight on the several parts on a straight line, thus preventing bending or other stresses or strains being set 30 up in the structure.

Referring to the drawings, Figure 1 is a side elevation of the complete assembly of all the parts of the shore.

Figure 2 is a plan view of the locking ring 35 and handle.

Figure 3 is a section on the line 3—3 of Figure 2, of the locking ring and handle.

Figure 4 is a side elevation of the detail 40 application of the locking ring to the supported and supporting parts, showing the positioning lug partially in section.

Figure 5 is a plan view of Figure 4 with the supported column in section.

Referring to the drawings, 1 is a body to 45 be supported such as a beam. This beam is engaged by a cap member consisting of a bottom plate 2, side plates 3, supporting buttresses 4, and a positioning ring 5. This ring 5 fits on the top of the supported column 6

50 which is usually a pipe. This pipe 6 is

adapted to telescope within a supporting column or pipe 7 and within the cap member 8 which is mounted on the supporting member. This cap member also is provided with a ring 9 and a reinforcing buttress 10. On top of the ring 8 is mounted a positioning lug 11 which is on the top thereof. Along the outer edge is a shoulder 12. Within the shoulder is a cutaway portion 13, either end of which is bordered by a wall 14. This cutaway portion 13 is open on the side towards the supported column 6. 13 is substantially rectangular and is adapted to receive the nose 15 of the locking ring 16.

This locking ring consists of a nose 15 which has a rounded surface 17 and a ring 16. The ring itself has an interior opening in the shape of an ellipse. The half of the opening on the upper edge of the ring towards the supporting or positioning lug is 70 adapted to engage with half of the supported member 6 at an angle to the vertical axis thereof. This engaging edge is designated 18. The other half of the supported column 6 is engaged on the other side below the plane of engagement on the side towards the positioning lug by the other half of the sharp edge on the ring which is designated 19. This sharp edge is in a plane substantially parallel to the plane of the sharp edge 80 18 and below it. The ring itself flares away from this sharp edge on this half of the ring in faces 20 and 21 which terminate in the upper edges 22 and lower edge 23 respectively. This side of the ring carries the 85 handle 24.

The nose 15 consists of a broad straight member providing a bearing surface that will not allow the ring to rock about its transverse axis nor to readily move about 90 its vertical axis as 15 engages snugly within the walls 12 and 14.

The ring is so arranged that when in locked position its upper surface is approximately inclined at an angle of 25° from the horizontal plane, but the handle is located in the horizontal plane so that it may be readily grasped for final locking or unlocking of the several parts to one another.

The provision of the edges as described, 100

provides a complete encircling of the supported member by sharp engaging edges with the parts. Adjacent edges are so arranged that these edges may be re-sharpened 5 without destroying the effectiveness of the ring.

In practice, the general adjustment of the parts is secured by placing the supported member within the supporting member and 10 the parts locked to one another by locking the clamping ring upon the supported member, while its nose rests on the positioning lug.

For the fine adjustment of the elevation of 15 the supported member I provide a telescoping screw 25 at the base of the supporting column. The head of this screw 26 carries a plate 27 which loosely guides it within the supporting column while the face of the supporting column at 28 rests upon the ring 29 having eyes 30. This ring is internally threaded at 31 to engage with the threads 32 on the worm 25. Thus, as the ring 29 is rotated on the screw 25, the height of the 20 supporting column 7 will be adjusted gradually.

In order to insure the alignment of the parts as nearly as possible on the vertical axis, the end of the worm is provided with 30 a ball 33 which fits within the socket 34 carried by the broad base plate 35 so that this universal joint provides an aligning member to accommodate differences in adjustment of the parts.

35 Thus the several parts may be put into position and locked and then be aligned and adjusted as to height.

While I have shown and described certain features as constituting my invention, it 40 will be understood that parts have been shown for purposes of illustration only, and that I do not care to be limited to such details, as obvious modifications will occur to a person skilled in the art.

45 Having thus fully described my invention, what I claim as new and desire to secure by Letters Patent, is:—

1. In combination, with a pair of relatively longitudinal adjustable members, one 50 having a supporting shoulder provided with a recess, a gripping ring having an opening therein adapted to freely accommodate the other of said members therein and having a ball-headed nose adapted to engage and to 55 be seated in the recess in said shoulder and gripping edges on the interior of said opening oppositely disposed, adapted to engage respective halves of the member extending therethrough whereby said members are supported in adjusted positions when said gripping ring is inclined at an angle thereto, and a handle integral with said gripping ring.

60 2. In combination, in a locking ring, of a positioning and supporting portion, a handle portion and interiorly disposed engaging

edges arranged in an ellipse, a portion of the interior of said ring adjacent engaging edges being cut away on either side of said edge in such a way that the engaging edges are formed by surfaces at right angle to 70 each other on the ring.

3. In combination with a pair of relatively extensible inner and outer members, one having an abutment on its inner end portion, of a gripping and locking device bearing against the abutment and having an opening therein through which the outer of 75 said members extends, said gripping member being in an inclined position when gripping the outer member, merging surfaces forming gripping edges on the inside of said opening and arranged at angles relatively to the axis of said members and adapted to grip the outer member, a projection rigid on said device to engage and bear against said abutment, whereby the gripping device is maintained in position and said outer member is locked in adjusted position, when endwise pressure is exerted on said members, or when said gripping edges of said device are 80 moved in engagement with the member adjacent thereto.

4. In combination with a pair of relatively extensible members, one having an abutment at its inner end provided with a 95 recess therein, of a ring, a supporting and positioning projection located on one edge of said ring on a tangent thereto and having a laterally extending nose adapted to rest in said recess, a handle attached to said ring, and gripping edges on the interior of the ring.

5. In combination, a supporting member, a supported member, a positioning lug on 100 said supporting member and having a recess 105 therein, a locking ring adapted to engage the supported member, a positioning and supporting projection on said locking ring and having a laterally extending nose engaging the positioning lug in said recess, and a handle 110 on said ring.

6. In combination, a supporting member and a supported member arranged in telescoping relation, a supporting ring on the inner end of the supporting member, a positioning lug having a recess formed on said supporting ring, a locking ring about the supported member, a positioning and supporting projection on said locking ring engaging the recess of the positioning lug, and a handle on said ring, said ring being provided with gripping edges on the interior thereof to engage the supported member, one of said gripping edges engaging the supported member at a different plane 120 than the opposite gripping edge.

7. In combination, a supporting member, a supported member, a positioning lug on 125 said supporting member, a locking ring adapted to engage the supported member, a 130

positioning and supporting portion on said locking ring engaging the positioning lug, and a handle on said ring, said ring being provided with engaging edges on the interior thereof, said edges being laid out on an ellipse, and the edges being arranged in halves, one half being in one plane and the other being in another plane to engage the supported member in different planes, and means associated with the supporting member for further adjusting the elevation of the assembled parts. ¹⁰

In testimony whereof I affix my signature.

DON W. SCHAEFFER.
